CUSHIONING MEMBER FOR ARTIFICIAL DENTURES

Frank E. Avery, Erie, Pa.

Application February 20, 1952, Serial No. 272,599

8 Claims. (Cl. 32—2)

1

This invention relates generally to artificial dentures and more particularly to novel cushioning and sealing members for disposal between the contact portion of the dentures and the gums of the wearer thereof.

The material forming artificial dentures must necessarily be comparatively hard. Many times, a denture is wearable with some degree of comfort shortly after it is molded and fitted into the mouth and after the high spots are scraped or ground therefrom; however, this comfort does not last very long inasmuch as there is a perceptible change in the size and contour of the gums as time goes on so that the denture becomes loose upon the shrinkage of the gums. This looseness also causes wedging, tilting, and loss of suction so that it makes talking and eating difficult and there is considerable discomfort. Soft rubber, leather, and other like materials have been attached to the contact surfaces of dentures in an attempt to cushion the impact between the dentures and the gums but it was found that these materials are comparatively hard and they do not give the denture wearer any more comfort than before because there is very little elasticity in the material and upon shrinkage of the gums, the dentures become loose. None of these prior cushioning members provide for changes in the size and contour of the gums. The surfaces of these cushioning members are comparatively unyielding. An attempt has been made to attach a diaphragm to the marginal edges of the contacting surfaces of artificial dentures in spaced relation from the contact surface thereof so as to form a chamber to hold a fluid. It was found that this type of cushioning member permits tilting at the point of pressure. When biting on one side of the denture, it is tilted and fluid in the chamber formed between the diaphragm and the contact surface of the denture passes to the opposite side of the chamber from the point of pressure so that there is a hard unyielding surface between the gum and contact surface of the denture as the pressure point inasmuch as the fluid at that point where pressure is applied is forced to another point in the chamber.

It is, accordingly, an object of my invention to overcome the above and other defects in cushioning and sealing members for dentures and it is more particularly an object of my invention to provide a cushioning and sealing member for a denture which is simple in construction, economical in cost, economical in manufacture, and efficient in operation.

2

Another object of my invention is to provide a cushioning and sealing member for a denture which provides for changes in size and contour of the gums of the wearer of the denture.

5 Another object of my invention is to provide a cushioning and sealing member for a denture which prevents sliding of the denture and chattering thereof.

Another object of my invention is to provide 10 a cushioning and sealing member for a denture which maintains a sealed connection between the denture and the gum so as to hold the denture in a predetermined position.

Another object of my invention is to provide 15 a cushioning and sealing member for a denture which is extremely soft and yieldable and which is easily replaceable.

Another object of my invention is to provide 20 a cushioning and sealing member for a denture which may be adapted for use with old dentures without any change therein.

Other objects of my invention will become evident from the following detailed description, taken in conjunction with the accompanying 25 drawings, in which

Fig. 1 is a plan view of a lower denture with my novel cushioning and sealing members associated therewith;

Fig. 2 is a view taken on the line 2—2 of Fig. 1;

Fig. 3 is a plan view of an upper artificial denture with my novel cushioning and sealing members associated therewith;

Fig. 4 is a view taken on the line 4—4 of Fig. 3;

Fig. 5 is a view taken on the line 5—5 of Fig. 3; 35 and

Fig. 6 is a plan view of an upper artificial denture with a one piece cushioning and sealing member associated therewith.

Referring now to the drawings, I show in Figs. 40 1 and 2 a plurality of arcuate shaped, elongated, flexible, closed cushioning and sealing members 1 substantially U-shaped in cross section disposed in engagement with the contacting portion 2 of a lower plate or artificial denture 3. The cross section of the cushioning members 1 is shaped to conform to the shape of the gums of a wearer of the denture 3. The ends of the cushioning members 1 preferably overlap each other at 4 so as to provide a continuous seal around the contacting surface of the lower denture 3; however, it is not necessary that the cushioning members 1 overlap each other. It will be evident that the cushioning members 1 may be made flat and bent or formed 45 into the shape of cross section as shown in Fig. 55

2 to correspond to the contour of the contacting surfaces of the artificial denture 3 and the gums of the wearer of the denture. The cushioning members 1 tend to shape themselves when they are in place in embracing relation with a denture. The cushioning members 1 are filled with any suitable type of fluid or semi-fluid such as water, air, gas, oil, paraffin, or any other suitable cushioning fluid or semi-fluid. The body of the cushioning members 1 is preferably made of a very soft elastic rubber or plastic composition but any other suitable soft pliable material may be utilized.

The cushioning members 1 may be attached to the denture by any suitable adhesive. Because 15 of the pliability of the cushioning members 1, there is a sealing action produced with the surfaces in contact therewith so that it is not absolutely necessary to use an adhesive to attach them to the denture 3.

Any old denture may be made tight by adding my novel cushioning members 1 thereto after there has been a shrinkage of the gums. It is merely necessary to lay them in engagement with the U-shaped contacting surface 2 of a lower plate 3 as shown in Figs. 1 and 2. I have shown three cushioning members 1 overlapping each other. More may be utilized. The reason for using more than one cushioning member is that it has been found that where only one cushioning member 1 is used in engagement with the contacting surface of a denture, when the denture is tilted by biting on one side thereof, fluid in the container passes to the opposite side thereof from the pressure point so that there is no fluid between the contacting surface of the denture and the gum at the pressure point, thereby resulting in sharp pain and discomfort to the wearer of the denture.

By providing a plurality of cushioning members as shown in the drawings, the pressure is only on one cushioning member which covers only a comparatively small area so that there is no place for the fluid to be transferred. This results in a soft, pliable comfortable cushion between the gums and the denture and also a perfect seal between the cushioning members and the denture and gum surfaces which it contacts.

Figs. 3, 4, and 5 show an upper plate or denture 12 with my arcuate, soft, pliable, closed cushioning and sealing members 10 disposed around the margin of the contacting surface 11 of the upper denture 12 with the ends thereof in overlapping relationship so as to form a continuous seal with the margin of the contacting surface 11 of the denture 12. Overlapping is not necessary for the efficient functioning of my cushioning members 10. The members 10 comprise very thin bodied, soft, closed containers with a suitable fluid or semi-fluid therein such as air, water, gas, oil, paraffin, gum, or the like. The container is preferably made of a very soft pliable rubber or plastic composition; however, any other suitable material may be utilized. The cushioning members 10 may be attached to the upper plate 12 by any suitable adhesive if desired. The cushioning members 10 are disposed in the conventional marginal groove in the upper plate 12 as shown in Figs. 4 and 5 and they are somewhat U-shaped in cross section to more nearly conform to the contour of the gums so as to make a more perfect fit between the gums and the cushioning members 10 and to provide a perfect seal therebetween. The cushioning members 10 extend completely around the margin of the contacting

surface of the upper denture 12 and they sealingly engage the denture and gum surfaces, thereby creating a suction to hold the upper denture in place. The cushioning members 10 provide a soft pliable cushion as well as a seal.

In Fig. 6, I show an upper plate or denture 30 with a one piece container member 31 having a fluid or semi-fluid therein. The member 31 is shaped to cover the margin of the contacting portion of the plate or denture 30 to act as a cushioning and sealing member.

It will be evident from the foregoing description that I have provided novel cushioning and sealing members for artificial dentures which preferably comprise a plurality of elongated, soft, pliable separate containers made of an extremely flexible and elastic material filled with a fluid or semi-fluid, which need not be vulcanized or otherwise sealed or joined to a denture, which are easily placeable and replaceable, which reduce the possibility of complete collapse of the cushioning members because of the number of containers, which accept a load where the pressure is applied and do not permit the denture to rock or tip, and which provide an area on the upper denture that is sealed in but has no cushion to give a low pressure area necessary to hold an upper denture in position by suction.

Various changes may be made in the specific embodiment of my invention without departing from the spirit thereof or from the scope of the appended claims.

What I claim is:

1. In combination with an artificial denture, comparatively soft, pliable, filled, elongated closed container members disposed on the gum contacting surface of said denture, the ends of said container members overlapping each other.
2. In combination with an artificial denture, U-shaped, comparatively soft, pliable, filled, closed container members overlapping each other and engaging the contacting surface of the denture for sealingly engaging the gum of a wearer of the denture.
3. In combination with an upper denture, a plurality of comparatively soft, pliable, elongated, filled, closed container members disposed in engagement with the margin of the contacting surface of said denture, the ends of said container members being in overlapping sealing relationship.
4. In combination with an upper artificial denture, comparatively soft, pliable, elongated, filled, closed container members U-shaped in cross section aligned around the margin of the contacting surface of the denture for sealingly engaging the gums of a wearer of the denture.
5. A denture structure comprising a plate member, a plurality of teeth carried by said plate member, said plate member having a contacting surface for contacting the gums of a person wearing the plate, and aligned, comparatively soft flexible inflated container members disposed on the contacting surface of said denture, said container members being generally U-shaped in cross section.
6. In a denture, the combination of a structure having a plurality of teeth mounted thereon, a contacting surface substantially the contour of the gums of a wearer of said denture, and inflated, flexible, comparatively soft container members disposed on the contacting surface of said denture in overlapping relationship disposed between the gums of a person wearing the denture and the denture.

7. In a denture as set forth in claim 6 wherein said container members are generally U-shaped in cross section.

8. In combination with an upper artificial denture, a comparatively soft, pliable, elongated, filled closed container member U-shaped in cross section disposed around the margin of the contacting surface of the denture for sealingly engaging the gums of a wearer of the denture.

FRANK E. AVERY. 10
